DESIGN FOR A COMBINED SLIP AND SHAPED BRASSIÈRE.

Application filed April 18, 1925. Serial No. 13,160. Term of patent 3½ years.

To all whom it may concern:

Be it known that I, TAUBE DAVIS, a citizen of the United States, and a resident of the city of New York, borough of Manhattan, in the county and State of New York, have invented a new, original, and ornamental Design for Combined Slip and Shaped Brassière, of which the following is a specification, reference being had to the accompanying drawing, forming part thereof.

Figure 1 is a perspective view of a combined slip and shaped brassière, showing my new design.

Figure 2 is a two-third rear perspective view of the garment shown in Figure 1.

The dominant feature of the design resides in the brassière top ornamented at the front center and with fold effects leading laterally therefrom, and having lace at top and bottom.

I claim:

The ornamental design for a combined slip and shaped brassière, substantially as shown and described.

TAUBE DAVIS.
